JOSEPH BIJUR, OF NEW YORK, N. Y., ASSIGNOR TO BIJUR MOTOR APPLIANCE COMPANY, OF HOBOKEN, NEW JERSEY, A CORPORATION OF DELAWARE.

ELECTRICAL APPARATUS FOR MOTOR-VEHICLES.

1,375,998.

Specification of Letters Patent.

Patented Apr. 26, 1921.

Application filed June 27, 1918. Serial No. 242,247.

To all whom it may concern:

Be it known that I, JOSEPH BIJUR, a citizen of the United States, and a resident of the borough of Manhattan, in the city, county, and State of New York, have invented an Improvement in Electrical Apparatus for Motor-Vehicles, of which the following is a specification.

This invention relates to electrical apparatus, and with regard to certain more specific features, to such as are employed in connection with motor vehicles for internal combustion engines.

One of the objects of the invention is to provide inexpensive and compact electrical apparatus for motor vehicles.

Another object is to provide an arrangement of apparatus of the above type which arrangement shall be convenient of application with respect to engines of various designs.

Other objects will be in part obvious and in part pointed out hereinafter.

The invention accordingly consists in the features of construction, combinations of elements and arrangement of parts which will be exemplified in the construction herein-after set forth, and the scope of the application of which will be indicated in the following claims.

In the accompanying drawings wherein is shown one of various possible embodiments of the several features of this invention, Figure 1 is an end view of a machine showing my invention, Fig. 2 is a side view thereof partly in section, only a fragment of the generator being shown.

Similar reference characters refer to similar parts throughout the different views of the drawings.

Referring now to these drawings there is shown a generator 1 having a yoke 2 and an end head 3 closing one end of said yoke. Any desired type of regulation may be employed. The drawing shows by way of example a lever L for manually adjusting the position of a third brush (not shown), which regulates the machine in a well known manner. The end head 3 has a cylindrical supporting portion 4 for bearing 5 in which armature shaft 6 turns. The bearing supporting portion 4, as shown, projects somewhat beyond the relatively flat face of end head 3, and the bearing is preferably lubricated by oil to be fed through a passage 29

formed integral with the end head and communicating by way of the bearing with either reservoir 30 or 31 cast integrally with the end head 3. As one of the two reservoirs is ordinarily superfluous, reservoir 31 may be plugged and reservoir 30 is shown in use having therein a wick 30' for feeding oil to the bearing. The purpose of providing for two reservoirs although one only is in use will appear below.

Formed preferably integrally with end head 3 and symmetrically and integrally with reservoirs 30 and 31, there is a casing 7 adapted to inclose preferably an automatic electromagnetic switch construction 8. Automatic switch 8 need not be described in detail as its construction is no part of my present invention. It may be simply noted that the function of this switch is to automatically form an electrical connection between the generator and a battery when the voltage of the generator exceeds that of the battery by a substantial amount, this, for purposes of charging the battery, and to automatically open such connection when the voltage of the battery substantially exceeds that produced by said generator for the purpose of preventing the battery from discharging through the generator. The casing 7, as shown, is preferably in the form of a rectangular box, having a base 9 preferably formed integrally with and in the same plane as the flat portion of end head 3. The sides 10, 11, 12 and 13 of said box are preferably formed integrally with the base and with each other and extend at right angles to said base and away from said generator. One side of said box, in the drawing, side 12, is preferably located in close proximity to bearing supporting portion 4. It is to be understood that this box need not have the shape set forth, but its sides may be, geometrically considered, of any closed cylindrical form. A cover 14 secured by screws 15 or the like preferably closes said box or casing. On one side of said box is preferably located a cover 16 in which a fuse (not shown) is disposed. This fuse is preferably in series with the shunt field of the generator for the well-known purpose of preventing the field from burning out in case the generator operates on open external circuit. The terminal 18 preferably projects through a side of the box or casing 7 and is inclosed in an insulating terminal 110

cover 19, preferably made of rubber and having a main portion 20 directly covering said terminal and a tubular portion 21 through which a lead to the external circuit extends. The drawings show a single wire or grounded arrangement in which one terminal (not shown) is connected to a metallic construction, such as the engine, or the frame of the vehicle. If my construction were to be adapted for a two wire system, each terminal would preferably be inclosed in a separate terminal cover 19. Formed preferably in the part of the construction common to the flat portion of end head 3 and the bottom 9 of the casing or box, there are preferably openings 17 through which the automatic switch 8 is electrically connected with the generator proper. The circuits are not described in detail as they are no part of my present invention.

The bearing supporting portion 4, as shown in Fig. 2, is formed of lesser thickness of metal near its free end, forming a pilot as shown at 32, the junction of pilot 32 and remaining part of the bearing supporting portion 4 forming a shoulder 33. Formed integrally with end head 3 and bearing supporting portion 4 is platform 34 having preferably tapped openings 35 and 36, the former adjacent the bearing supporting portion and the latter adjacent the free end of said platform. An identical platform similarly perforated is formed diametrically opposite the platform just described, the two platforms being symmetrically disposed with respect to a diameter running the length of the paper in Fig. 1. The tops of the platform are preferably in the same plane as shoulder 33.

An ignition support 25 is preferably secured to the end head by screws passing through integral lugs on said support as shown at 23 and 24. The ignition housing consists preferably of a tubular portion 26 telescoped over the end of bearing supporting portion 4 as shown at 27 and abutting shoulder 33. The lowermost part of said tubular portion as shown in the drawing, is preferably flattened and slightly spaced from side 12 of the box or casing 7 as at 56. A second tubular portion 28 is shown somewhat to one side of the tubular portion 26 and at right angles thereto, the openings in said tubes communicating as shown. The ignition support is preferably cast from a single piece as shown in the drawing. This ignition support as shown in the drawings is preferably formed symmetrically with respect to a bisecting plane parallel to the flat surface of end head 3. On each side of said support and in the plane of the corresponding end of tubular portion 26 there is a flat surface 55 of substantially the form of platform 34.

Preferably keyed to an extension 37 of

shaft 6, there is a spiral gear 38 preferably held against longitudinal movement with respect to said extension by a sleeve 39, one end of which abuts a washer 40 which in turn is held against shoulder 57 on the shaft, 70 the spiral gear 38 being prevented from moving off the shaft by a nut 41 threaded to the end of said shaft. The gear 38 is substantially concentric with the tubular portion 26 of the ignition support. Extending 75 within tubular portion 28 and preferably supported thereby to be driven by gear 38, there is an ignition unit, only a fragment of which is shown on the drawing. This unit consists of a substantially vertical shaft 80 43 having on the lower end thereof a spiral gear 44 adapted to mesh with gear 38 for the purpose of driving shaft 43 from the generator shaft 6. Shaft 43 drives preferably both a timer and a distributor, which latter 85 elements are not shown as they are no part of my invention. Shaft 43 is preferably inclosed in an insulating casing 42 fitting snugly within tubular portion 28 and having preferably an enlarged portion 45 resting on 90 the free end of said tubular portion. The casing 42, also, has preferably a peripheral groove as shown at 46 coacting with a set-screw 47 inserted from the exterior of tubular portion 28, the set-screw effectively 95 preventing the ignition unit from being bodily raised by the action of gear 38. The free end of the ignition support is preferably fashioned in the form of a clamp, there being a longitudinal split 48 between two integral lugs 49 and 50 adapted to be drawn together by a bolt 51 for the purpose of aiding in firmly maintaining the ignition unit in position. A spring metal cover 52 preferably closes the opening in tubular portion 26 100 and is preferably secured by staking. The casting 25, it is thus seen forms not only an ignition support, but a housing for the ignition transmission.

Owing to the symmetrical form of the ignition support and to the symmetrical arrangement of the two platforms, one of which is shown at 34, it is clear that the ignition support 25 may be secured either as shown in the drawing with lug 53 secured at 23 and lug 54 at 35, or said support may be disposed symmetrically to the position just described by being laid on its other side with flat surface 55 covering platform 34, lug 53 being secured at 36 and lug 110 54 at 36'. By this arrangement the ignition support may with equal facility be assembled with the ignition driving shaft 43, either toward the left of the generator shaft as shown in Fig. 1, or symmetrically to the 115 right of said shaft.

Owing to the great variety of designs of internal combustion engines and to the great variety of arrangements of accessories thereof, it is clear that if the ignition drive were 120 125 130

unalterably disposed in a single position on the generator, interference with some part of the engine, or with one or more of its accessories would result unless a great number of special designs were made. By my invention, one design assembled in either of two ways enables me to readily apply my apparatus to a relatively great variety of engines.

10 On engines employing magneto ignition or in case it is not desired to operate the ignition from the generator, I simply dispense with the ignition support 25 and the remaining apparatus constitutes a complete 15 operative unit without any change whatsoever. In this case, I am also enabled to dispose the housing of the generator in any angular position about its axis, so that the casing 7 and its inclosed apparatus 8 may 20 readily be arranged with respect to substantially any engine, to avoid interference, with other accessories or engine parts. In case the angle selected in any case is such that reservoir 30 assumes substantially the position occupied by passage 29, the functions 25 of these two parts would be reversed, reservoir 30 being then employed as an oil passage and passage 29 being then closed at its bottom and having a wick inserted 30 therein to serve as a reservoir. On the other hand if the preferred angular position of the head be such as to place plugged reservoir 31 near the top of the construction, the plug would then be removed and element 31 35 would then serve as an oil passage. The three elements 29, 30 and 31 for the application and storing of lubricating material are ordinarily sufficient as appears from the above description to secure proper lubrication 40 of the bearing regardless in what angular position the apparatus be mounted. There is always at least one passage in the upper half of the head which serves for entry of oil and at least one reservoir in the 45 lower half for storing the oil.

It will thus be seen that there is herein described apparatus in which the several features of this invention are embodied, and which apparatus in its action attains the 50 various objects of the invention and is well suited to meet the requirements of practical use.

As many changes could be made in the above construction, and many apparently 55 widely different embodiments of this invention could be made without departing from the scope thereof, it is intended that all matter contained in the above description or shown in the accompanying drawings shall 60 be interpreted as illustrative and not in a limiting sense.

Having described my invention what I claim as new and desire to secure by Letters Patent is:

65 1. A power transmission, comprising a

driving shaft, a driven shaft, said driven shaft being in a plane at right angles to said driving shaft, and a reversible transmission casing whereby said driven shaft may be driven from either side of said driving shaft. 70

2. A power transmission, comprising a driving shaft, a driven shaft, in a plane at right angles to said driving shaft, and a reversible combined transmission housing 75 and carrying member for said second shaft, whereby said transmission may be assembled with said driven shaft at either side of said driving shaft and extending in either direction therefrom. 80

3. In electrical apparatus for motor vehicles, in combination, an extended generator shaft, a shaft for ignition apparatus, in a plane at right angles to said generator shaft, and a casting for maintaining said second shaft in position, and for inclosing the transmission between said shafts, said casting being bilaterally arranged symmetrically with respect to a plane at right angles to said generator shaft, whereby said casting may be arranged to dispose said second shaft toward either side of said generator shaft. 85 90

4. In electrical apparatus for motor vehicles, in combination, a generator, a housing carried by the end thereof, said housing being substantially symmetrical with respect to a plane perpendicular to the axis of said generator, the end of the shaft of said generator extending into an opening in said 100 housing, and a shaft for ignition apparatus extending into another opening in said casting, and in a plane at right angles to said generator shaft, and a transmission between said shafts inclosed in said housing. 105

5. In electrical apparatus for motor vehicles, in combination, a generator, a housing secured to the end thereof, said housing being substantially symmetrical with respect to a plane perpendicular to the axis of 110 said generator, the end of the shaft of said generator extending into an opening in said housing, and driving a spiral gear, and a shaft for ignition apparatus extending into another opening in said casing, to one side 115 of said generator shaft and having a second spiral gear co-operating with said first spiral gear.

6. In electrical apparatus for motor vehicles, in combination, a generator having 120 an end head, a housing having a tubular cavity to one side of the generator shaft secured to said end head, said housing being substantially symmetrical with respect to a plane parallel to said end head, said end 125 head having symmetry for permitting said housing to be secured thereto, with said cavity located at either side of said shaft, a shaft for driving ignition apparatus, disposed in said tubular cavity, and a trans- 130

mission for driving said shaft from said generator.

7. In electrical apparatus for motor vehicles, in combination, a generator, an integral housing, having one cavity substantially concentric with the armature shaft, for inclosing an extension thereof, and a second cavity in a plane at right angles to said shaft, for inclosing a shaft for ignition apparatus, the junction between said cavities, being adapted to inclose a pair of meshing spiral transmission gears for driving said second from said first shaft, said gears being each smaller in diameter than the corresponding housing cavity.

8. In electrical apparatus for motor vehicles, in combination, a generator having an end head, an armature shaft projecting beyond said end head, a spiral gear fastened to said projecting portion, a casing for electromagnetic apparatus having a side below and adjacent to said projection, a housing inclosing said spiral gear, in proximity to said side of said casing and secured to said end head, said housing having a tubular portion to one side of said shaft, leading to said spiral gear, an ignition driving shaft within said portion, and having a member thereon coöperating with said spiral gear,

30 said housing being symmetrical with respect to a plane parallel to said end head, whereby said housing may be reversibly mounted, with said ignition driving shaft on either side of said generator shaft.

35 9. In electrical apparatus for motor vehicles, in combination, a generator having an end head, an armature shaft projecting beyond said end head, a spiral gear fastened to said projecting portion, a housing

40 inclosing said gear, and secured to said end

head, said housing having a tubular portion adjacent said shaft, and at right angles thereto, said tubular portion extending to said gear, the free end of said portion having a clamping arrangement, said housing 45 being symmetrical with respect to a plane parallel to said end head, whereby said housing may be disposed with said tubular portion on either side of said shaft, and an ignition drive shaft may be disposed in said 50 tubular portion and driven from said armature shaft.

10. In apparatus of the class described, in combination, an end head, having a bearing surface therein, a plurality of radial 55 passages integral with said end head, and leading to said bearing surface, whereby, when said head is disposed in substantially any position other than horizontal some one of said passages may be used for feeding lubricant, and another when sealed at its outer end, as a lubricant reservoir.

11. In apparatus of the class described, in combination, a dynamo, including an end head, said head having a bearing surface therein, three integral radial passages on said end head, and leading to said bearing surface, a casing for an automatic switch formed integrally with said end head, substantially symmetrically with said 65 passages and integrally with two of them, whereby when said dynamo is mounted in substantially any non vertical position, some one of said passages may be used for feeding lubricant and another when sealed 70 at its outer end, as a lubricant reservoir.

In testimony whereof, I have signed my name to this specification this 5th day of June, 1918.

JOSEPH BIJUR.
